UNITED STATES PATENT OFFICE.

GERHARD P. PLISCHKE AND HEINRICH BRUECKEL, OF MILWAUKEE,
WISCONSIN.

CLAMP.

SPECIFICATION forming part of Letters Patent No. 447,526, dated March 3, 1891.

Application filed July 26, 1890. Serial No. 359,973. (No model.)

To all whom it may concern:

Be it known that we, GERHARD P. PLISCHKE and HEINRICH BRUECKEL, of Milwaukee, in the county of Milwaukee, and in the State of Wisconsin, have invented certain new and useful Improvements in Clamps; and we do hereby declare that the following is a full, clear, and exact description thereof.

Our invention relates to clamps for holding separate parts of picture-frames and other structures together while being glued; and our invention consists in certain peculiar and novel features of construction and arrangement as hereinafter described, and pointed out in the appended claims.

In the drawings, Figure 1 is a view in side elevation and partly in longitudinal section of a clamp constructed in accordance with our invention. Fig. 2 is an end elevation of the same, partly in transverse section on the line 2 2 of Fig. 1. Fig. 3 is a plan view of the fixed arm and a horizontal cross-section on the line 3 3 of Fig. 6. Fig. 4 is a plan view and partial horizontal section of our improved clamp, the section being taken on the line 4 4 of Fig. 1. Fig. 5 is a detached view in side elevation of the detachable pivot-plate for the cam-lever. Fig. 6 is an inner side elevation of the upper part of the rigid arm of the clamp.

The objects of our invention are to provide a clamp of simple and durable form, the clamping-surfaces of which shall automatically adjust themselves to inequalities in the parts of the structure being clamped, and the clamping-lever, of which shall operate strongly and not be liable to dislocation from its clamping position by reason of blows or knocks either upon the clamp or upon the work being clamped. These objects we attain by virtue of the construction which we will now proceed to describe.

In the said drawings, A designates the main bar of our improved clamp, said bar being of L shape and the longer arm A' being serrated longitudinally upon its upper edge, substantially as shown at a. The upper end of the shorter arm A² of this bar is formed with a lower transverse rib or shoulder b, an upper transverse rib or shoulder b', and an intermediate transverse rib or shoulder b², said ribs or shoulders being all upon the same

side of the arm A² and being also parallel with each other. An arm C extends outwardly at right angles from the upper end of said arm A² of bar A, and the outer end of this arm is formed with an eye c to receive a pivot-stud d of a cam-lever D, to be herein-after more fully described.

F designates a detachable pivot-plate, which is of substantially square form and which is provided with a lateral arm or extension f, having an eye f' in its outer end, which, when the pivot-plate is in operative position, coincides with the eye c, before referred to, and receives a pivot-stud d' of the cam-lever D, said stud extending oppositely from the stud d, previously mentioned. The pivot-plate F is attached removably to the upper end of the arm A², and between the ribs b b' of the plate F resting, respectively, upon the ribs or shoulders b b'.

In order to prevent slipping or accidental displacement of the pivot-plate F, it is provided with a lug f⁴ adjacent to its rib f³, and the upper rib b' is formed with a recess b³ to receive said lug f⁴.

H designates an elongated clamping-rod which works between the ribs b' b² as guides. The inner end of this clamping-rod is formed with a spherical head h, which enters a corresponding socket i, formed in the back of a clamping-head I. The margin of this socket is preferably slotted or cut out to form fingers i', as best shown in Fig. 4, and which fingers are bent inwardly to embrace the spherical head h, and a friction-ring j is interposed between said inwardly-bent fingers and said head, so as to stiffen the connection with the spherical head sufficiently to prevent the clamping-head from dropping downward while permitting it to vary its position to accord with variations of the surfaces to be clamped. The opposite end of the rod H is formed with a longitudinal loop h', which embraces the stud d' of the cam-lever D. The extreme outer end of the rod H beyond the outer margin of this loop is formed with two studs h² h², which embrace a lateral marginal rib d² of the cam-head D'. This cam-head is of substantially ovoid form, and the rib d² is consequently of like form, there being an in-

ward curve or bend in the outer edge of the cam-head and rib at the point d^3 , (shown in dotted lines in Fig. 3,) whereby a saving of metal is effected.

- 5 K designates the movable jaw of the clamp, this jaw being provided at its outer or upper end with bifurcations having a transverse recess in one edge thereof, (to receive a cross-pin k' , hereinafter named,) and the said jaw 10 is further provided at its inner or lower end with an eye or loop k to embrace the outer end of the arm A' . The upper surface of this eye or loop is downwardly and outwardly inclined, so as to operate at its edge K' as a 15 tooth to engage the serrations a . The upper end of this jaw K is provided with a cross-pin k' , which is embraced by the converging ends of two studs m of a clamping-head L. Shoulders k^2 k^3 are formed on the bifurcated end 20 of the jaw K above and below the pin k' , so as to limit the pivotal movement of the clamping-head L upon the pin. In order to retain the movable jaw upon the bar A' , a detachable head N is attached to the outer end of 25 the bar by rivets n , as shown.

The operation of our device will be readily understood from the foregoing description of its construction, taken in connection with the accompanying drawings.

- 30 In use the arm A' is vertical, with the arm A^2 projecting horizontally above the movable jaw K, the head N keeping the movable jaw K from accidentally dropping off the lower end of the said arm A' . The wood or other 35 material being operated upon is clamped between the clamping-heads I and L.

Heretofore clamps analogous in many respects to ours have been made wherein the clamping-rod which was operated by the cam-40 lever was connected to the cam-rib at a point between the pivot of the cam-head and the clamping-head on said rod. The consequence of this construction was that when in use any pounding upon the wood or other material 45 held by the clamp would serve to loosen the hold of the said rod on the said rib and allow the cam-lever to slide and drop, thereby unclamping the material; but with our construction this point of contact between the clamp-

ing-rod and the cam-rib is at the extreme 50 outer end of said rod, (which is the extreme upper end thereof in use,) and therefore the contact of the parts II h^3 h^2 with the rib d^2 will not be disturbed by such pounding and the material will always remain tightly 55 clamped until the cam-lever D is voluntarily moved.

By reason of making the described retaining-head N detachable it can be removed, in the event of the jaw K becoming broken or 60 injured, for the replacing of a new jaw, and then the head N can be restored to place, as before.

Having thus described our invention, what we claim as new therein, and desire to secure 65 by Letters Patent, is—

1. In a clamp, the combination of an angular clamping-bar, with a movable jaw at one end carrying a clamping-head and a clamping-rod sliding in the other end of said bar and provided with a clamping-head at its lower or inner end and a loop at its upper or outer end, a cam-lever pivoted to said bar and having a stud projecting through the loop of said clamping-rod, and a marginal cam-track, the 70 extreme outer or upper end of said clamping-rod engaging with said cam-track at a point between said stud and the outer end of the cam-lever, substantially as set forth.

2. In a clamp, the combination, with an angular bar, of a movable jaw sliding on the same and having a bifurcated outer end and a transverse recess in one edge of said bifurcations, a pin located in said recess, and a clamping-head provided with studs on its reverse side passing between said bifurcations and straddling said pin and having converging ends bent around said pin, substantially 85 as set forth.

In testimony that we claim the foregoing 90 we have hereunto set our hands, at Milwaukee, in the county of Milwaukee and State of Wisconsin, in the presence of two witnesses.

GERHARD P. PLISCHKE.
HEINRICH BRUECKEL.
